UNITED STATES PATENT OFFICE.

JOHN J. CLUIN, OF LOWELL, MASSACHUSETTS.

DESIGN FOR A BADGE.

SPECIFICATION forming part of Design No. 28,884, dated June 21, 1898.

Application filed May 2, 1898. Serial No. 679,544. Term of patent 7 years.

To all whom it may concern:

Be it known that I, JOHN J. CLUIN, a citizen of the United States, residing at Lowell, in the county of Middlesex and Commonwealth 5 of Massachusetts, have invented and produced a new and original Design for a Badge, of which the following is a specification, said design being represented in the accompanying drawing.

10 The leading feature of my design consists in a circular panel surmounted by a Latin cross and containing a representation of the landing of Columbus and arranged centrally upon a cross, behind which are arranged 15 crossed swords, only the hilts and points of which are visible.

A represents an equal-armed cross having at the outer ends of its arms angular points a^1 and having the outer corners concaved at a^2 . The cross A is provided at its periphery 20 with a double raised border a^3 .

B indicates the circular panel, which carries the representation of the landing of Columbus; C, the Latin cross, surmounting the panel B in the panel a^4 , included between the 25 said panel B and the border a^3 . The panel a^4 bears also on opposite sides of the panel B a sextant D, an anchor, and rope E, and below the panel B a pair of swords F F', crossed behind fasces G.

30 A pair of crossed swords H H' is represented as arranged behind the cross A, the hilts $h h'$ and points $h^2 h^3$ of said last-named swords showing above and below in the spaces between the arms a of said cross A.

35 The cross A is surmounted by a helmet I, provided with a crest i.

I claim as my invention—

40 The design for a badge, substantially as herein shown and described.

In witness whereof I have signed this specification, in the presence of two attesting witnesses, this 29th day of April, A. D. 1898.

JOHN J. CLUIN.
